Patented July 12, 1921.

UNITED STATES PATENT OFFICE.

PRESTON ERVIN, OF EMPORIA, KANSAS.

BERRY CLEANER AND STEMMER.

1,384,455.

Specification of Letters Patent. Patented July 12, 1921.

Application filed March 14, 1921. Serial No. 451,998.

To all whom it may concern:

Be it known that I, PRESTON ERVIN, a citizen of the United States, residing at Emporia, in the county of Lyon and State of Kansas, have invented certain new and useful Improvements in Berry Cleaners and Stemmers, of which the following is a specification, reference being had to the accompanying drawings.

10 This invention relates to devices for stemming berries, and particularly to means for stemming gooseberries or like berries.

The general object of my invention is to provide a very simple and effective device 15 for this purpose so constructed that the berry is carried around a number of times in contact with an exterior wall whereby to rub off and detach the stem of the gooseberry from the berry itself.

20 A further object is to provide a device of this character which is adapted to receive and stem berries of various diameters.

And a further object is to provide means 25 for separating the stems, dirt, trash, etc., from the berries.

Other objects will appear in the course of the following description.

My invention is illustrated in the accompanying drawings, wherein:—

30 Figure 1 is a vertical sectional view of a gooseberry stemmer constructed in accordance with my invention;

Fig. 2 is a section on the line 2—2 of Fig. 1;

35 Fig. 3 is an enlarged top plan view of the berry carrier.

Referring to these drawings, 10 designates two sections, each section being formed with confronting, semi-circular, longitudinal

40 grooves 11, which sections, when placed together, provide a circular, vertical passageway extending the full length of the sections. These sections in ordinary use are approximately 9" in length and the bore or pas-

45 sageway, when the sections are in contact with each other, is approximately 2" in diameter. The confronting faces of the passageway formed of the two sections are lined with cloth 12. These sections, as illustrated, 50 are rectangular in form and are held to each other by means of oppositely disposed clamps and supports.

At one side of the body formed by the sections 10 there is a longitudinally extending 55 rod or strip 13 of metal which extends a distance above the sections and which ex-

tends at least to the lower ends of the sections, this rod 13 or supporting strip being formed at spaced points with a pair of angularly bent, transversely extending clamps 60 14 bent at their ends so as to embrace the blocks 10 and afford outwardly projecting terminal portions 15. Opposite the supporting rod 13 there is disposed a like supporting rod 16 which is provided with clamps 17 of 65 the same construction as the clamps 14 and confronting the same, the angularly bent terminal ends of the clamps 17 and 14 being connected by bolts 18 which pass through perforations in the terminals of the clamps, 70 these bolts carrying coiled compression springs 19 which bear against the terminal ends of the clamps, thus forcing said clamps 75 yieldingly toward each other and thus holding the sections in yielding relation to each other. The clamps 14 and 17 are attached to the sections by screws, pins or in any other suitable manner.

The upper ends of the strips 13 extend over the upper ends of the sections 10 and 80 then extend upward and outward in divergent relation to support a hopper 20, which at its lower end discharges into the upper end of the passageway 11. This hopper 20 is preferably of cloth but any other suitable material may be used, and the hopper is supported by means of the frame formed by the strips 13 and 16. The upper portion of the strip 16 above the blocks is supported by means of a brace 21 and carries attached 85 to it in any suitable manner the radially extending brace 22 which is disposed within the hopper and forms a bearing for a horizontal shaft 24 and a vertical shaft 25. The shaft 24 carries upon its outer end the crank 90 handle 26 and upon its inner end the beveled gear wheel 27 which engages a beveled gear wheel 28 mounted upon the upper end of the shaft 25. The hopper is approximately 5" 95 deep and the shaft 25 may extend the full length of the passageway 11. Mounted upon the shaft 24 is a 5" wood pulley or band wheel 29.

At its lower end the supporting strip 16 is extended downward a considerable distance 105 below the lower ends of the sections 10 and is formed to provide a pair of clamping jaws 30, one of the clamping jaws having a screw 31 whereby it may be clamped against a table. The strips 13 and 16 also support below the 110 lower ends of the sections 10 an approximately circular chamber 31 having an in-

wardly extending, partially circular flange 32, and disposed within this chamber 31 and extending radially across and downward of this chamber is a chute or trough 33. The 5 stemmed berries are discharged from the lower end of the passageway 12 onto this trough 33 and roll down the trough and eventually drop off the lower end of the trough and in doing so cross an air passage 10 34. Mounted below the trough 33 is a fan 35 which preferably is a suction fan so as to draw air inward through the air passage 34 and discharge it outward. A screen 36 extends downward in front of the fan 35 so as 15 to prevent the stems, trash, etc., which is drawn by the fan from the berries from being discharged into the fan itself. The fan shaft 37 carries upon it a band wheel 38 $\frac{1}{2}$ " in diameter and this band wheel is driven by 20 means of an endless band 39 which extends upward around the band wheel 26.

Mounted upon the shaft 25 in any suitable manner and disposed within the passageway 12 is a cylindrical member 40 which is approximately 2" in diameter so as to approximately fill the passageway, this cylindrical member being formed with a plurality of helical grooves, shown as three in number, 25 41, 42 and 43. These grooves extend from 30 top to bottom of the member 40 and are illustrated as extending inward tangentially with reference to a circle whose center is the axis of rotation of the cylindrical member 40. These grooves, assuming that there are three 35 grooves, are respectively 8/16" deep, 10/16" deep and 12/16" deep measured on a dotted line *a—a* in Fig. 3. Thus these grooves have different areas so as to receive different sized berries, and where there are more than three 40 grooves they may range from 8/16" deep to 1" deep. Of course, it is obvious that the depth of these grooves 41, 42 and 43 may be changed to accord with the size of the berries being treated. The inner faces of the grooves 45 are lined with fine cloth, designated 44.

In the operation of this mechanism, the berries are placed in the hopper and at the same time the crank handle of the crank 26 is rotated to cause a counter-clockwise rotation 50 of the member 40 which constitutes a berry carrier. The rotation of the handle 26 will cause the very rapid rotation of the fan, which will draw a draft of air across the top of the berries dropping from the trough 33, 55 which will draw away from the berries the bits of stem, leaves, trash, etc., which may be brought down with the berries.

I do not wish to be limited to the use of a suction fan, as a blower might be used blowing a draft of air across and beneath the lower end of the chute 33 which would blow the dirt, trash, etc., away from the berries. I do not wish to be limited to the particular construction of the trough 33 as this may be 60 made in sections. As the handle 26 is ro-

tated, the berries drop into the upper ends of the spiral or helical grooves 41, 42 and 43 and the berries travel down these grooves and friction of the berries with the outside wall of the passageway 12 or with the cloth which lines this passageway causes the berries to rotate. The stems will come in contact with the relatively sharp edges which define the grooves 41, 42 and 43 and as a consequence the stems will be broken or rubbed off. The travel of the berries through these helical passageways cause the berries to rotate upon each other and against the fine cloth which lines the grooves and which lines the passageway 12, and as a consequence the berries will be polished, trash and dirt will be removed therefrom, the stems will be detached, and when discharged the berries will be in first-class shape for use.

While I have illustrated a particular form 85 of my invention which has been found to be thoroughly satisfactory in actual practice and which thoroughly cleans and stems the gooseberries without crushing them or marring the fruit, I do not wish to be limited to this, as it is obvious that many changes 90 might be made in the details of construction and arrangement of parts without departing from the spirit of the invention.

I claim:

1. A stemming and cleaning mechanism for goose berries comprising a body having a longitudinal passageway, a rotatable berry carrier disposed within the passageway and approximately filling the same and formed with a longitudinally extending, helical groove opening upon the ends of the carrier, a hopper discharging onto one end of said carrier, and means for forcing a blast of air across the path of movement of the berries after they have left the carrier whereby to separate the berries from stems and trash.

2. A fruit stemming and cleaning device of the character described comprising a body formed in two longitudinally extending half sections, means yieldingly urging said sections toward each other but permitting the sections to move away from each other, and a rotatable berry carrier disposed within the passageway and approximately filling the same and formed with a longitudinally extending, helical groove opening upon the ends of the carrier.

3. A fruit stemming and cleaning device of the character described comprising a body formed with a longitudinally extending, circular passageway, a berry carrier circular in cross section and approximately filling said passageway and rotatable therein, the berry carrier being formed with a plurality of longitudinally extending, helical grooves extending the entire length of the carrier, manually operable means for rotating said carrier, a hopper discharging into the upper end of the carrier, a chute upon which the

berries are discharged from the lower end of the carrier, and means for causing a blast of air to pass beneath said chute to thereby separate the stems from the berries.

5 4. A stemmer and cleaner for berries comprising a vertically disposed body having a central, vertically extending bore or passageway, the body being formed in two half sections, means yieldingly urging said sections toward each other but permitting the sections to move away from each other, a hopper discharging into the upper end of said passageway and a manually rotatable berry carrier disposed in said passageway 10 and circular in cross section and formed with a plurality of helical grooves extending from top to bottom of the carrier.

5 5. A stemmer and cleaner for berries comprising a vertically disposed body having a central, vertically extending bore or passageway, the body being formed in two half sections, means yieldingly urging said sections toward each other but permitting the sections to move away from each other, a hopper discharging into the upper end of said passageway, and a manually rotatable berry carrier disposed in said passageway 20 and circular in cross section and formed with a plurality of helical grooves extending from top to bottom of the carrier, said grooves having different depths and the grooves extending tangentially with relation to a circle concentric to the axial center of the carrier.

35 6. A berry cleaner and stemmer of the character described comprising a body having a vertical, axial, circular passageway for its entire length, the body being formed in two half sections, supporting members 40 attached to each of said sections and extending vertically upward, springs operatively engaging the sections and urging them toward each other, a hopper supported by said supporting members and discharging into 45 the upper end of the carrier, a shaft upon which the carrier is carried, manually operable driving means for the shaft, a trough

supported below the lower end of the carrier and onto which the carrier discharges, a fan mounted upon one of said supporting 50 members and disposed below the trough, and means connected to the manually operable driving means whereby the fan may be rotated at a relatively high speed.

7. A berry stemmer and cleaner comprising 55 a body having a vertical, circular passageway from top to bottom, the body being formed in two half sections, supporting members attached to the body and extending vertically upward above the same and below 60 the same, said supporting members having laterally extending clamps embracing the sections of the body, rods loosely connecting said clamps, springs carried by said rods and bearing against the clamps and urging 65 the same toward each other, a carrier circular in cross section and disposed within the passageway of the body, the carrier having a plurality of helical grooves extending from top to bottom of the carrier, said grooves 70 extending inward tangential to a circle concentric to the axis of rotation of the carrier, said grooves being of different depths, a hopper supported by said supporting members and discharging upon the upper end of 75 the carrier, a vertically disposed shaft supporting the carrier and extending upward through the hopper, a horizontal shaft operatively engaging the vertical shaft and having a crank handle, means carried by 80 said supporting members for supporting said horizontal and vertical shafts, a trough supported by the supporting members and to which the lower end of the carrier discharges, a suction fan disposed beneath said 85 trough and drawing air transversely across the lower end of the trough, band wheels mounted upon the first named horizontal shaft and upon the suction fan shaft, and an endless element connecting said band wheels. 90

In testimony whereof I hereunto affix my signature.

PRESTON ERVIN.
